(57) **CLAIM**

The ornamental design for an audio toy brick as shown and described.

DESCRIPTION

FIG. 1 is a top perspective view of an audio toy brick.

FIG. 2 is a bottom perspective view of the audio toy brick.

FIG. 3 is a second, top perspective view of the audio toy brick.

FIG. 4 is a second, bottom perspective view of the audio toy brick.

FIG. 5 is a front plan view of the audio toy brick.

FIG. 6 is a back plan view of the audio toy brick.

FIG. 7 is a side plan view of the audio toy brick.

FIG. 8 is a second, side plan view of the audio toy brick.

FIG. 9 is a top plan view of the audio toy brick.

FIG. 10 is a bottom plan view of the audio toy brick.

FIG. 11 is a top perspective view of a second embodiment of the audio toy brick.

FIG. 12 is a bottom perspective view of the second embodiment of the audio toy brick.

FIG. 13 is a second, top perspective view of the second embodiment of the audio toy brick.

FIG. 14 is a second, bottom perspective view of the second embodiment of the audio toy brick.

FIG. 15 is a front plan view of the second embodiment of the audio toy brick.

FIG. 16 is a back plan view of the second embodiment of the audio toy brick.

FIG. 17 is a side plan view of the second embodiment of the audio toy brick.

FIG. 18 is a second, side plan view of the second embodiment of the audio toy brick.

FIG. 19 is a top plan view of the second embodiment of the audio toy brick; and,

FIG. 20 is a bottom plan view of the second embodiment of the audio toy brick.
